UNITED STATES PATENT OFFICE.

SETH M. HINO, OF LANDER, WYOMING.

TELEPHONE-MOUTHPIECE.

1,219,459.

Specification of Letters Patent. Patented Mar. 20, 1917.

Application filed August 29, 1916. Serial No. 117,518.

To all whom it may concern:

Be it known that I, SETH M. HINO, a citizen of the United States, residing at Lander, in the county of Fremont and State of Wyoming, have invented certain new and useful Improvements in Telephone-Mouthpieces, of which the following is a specification.

This invention relates to an improved 10 telephone mouth-piece and the principal object of the invention is to provide a mouth-piece which will be antiseptic, a disinfectant being placed in a pocket formed in the mouthpiece and provided with outlet openings communicating with the interior of the mouthpiece.

Another object of the invention is to so 20 construct this mouth-piece that it will fit transmitters of a standard construction and to further so construct the mouth-piece that the same may be taken apart and the disinfectant removed and replaced when it loses its strength.

This invention is illustrated in the accompanying drawings, wherein:—

Figure 1 is a view showing the improved mouth-piece in longitudinal section and connected with a transmitter shown partially in section and partially in elevation.

Fig. 2 is a sectional view through the mouth piece taken along the line 2—2 of Fig. 1.

The body portion 10 of the mouth-piece is in the form of a shell having an outer wall 35 11 and an inner wall 12, the inner wall being extended to provide an externally threaded neck 13 which screws into the union or socket 14. This union or socket 14 is of the construction shown in Fig. 1 and is 40 provided with a perforated partition 15 and further is provided with an externally threaded neck 16 which will screw into the head 17 of a telephone transmitter of standard construction.

This device is put in place as shown in Fig. 1 and when in use produces a sanitary mouth-piece for the telephone. A disinfectant 18 of any suitable material is placed in the pocket 19 between the inner and outer 50 walls of the body portion 10 and is prevented from being wasted through the openings 20 of the inner wall by means of a protecting strip 21 which may be formed

of paper or any other suitable sheet material. When the disinfectant material loses 55 strength, the mouth-piece can be removed and when the coupling 14 is disconnected from the body portion, the disinfectant contained in the pocket 19 can be removed and a new supply of disinfectant material placed 60 in the pocket.

What is claimed is:—

1. A mouth-piece of the character described comprising a body portion having an inner and an outer wall providing a 65 pocket between the walls, a coupling having a perforated partition formed therein and provided at one end with an internally threaded socket and at the opposite end with an externally threaded neck, the inner wall 70 of the body portion being perforated and provided with an externally threaded neck extending beyond the outer wall and fitting into the internally threaded socket of the coupling, a disinfecting substance placed 75 within the pocket of said body portion, and a protecting sheet placed within the pocket and covering the opening formed in said inner wall.

2. A mouth-piece of the character described comprising a body portion having an outer wall and an inner wall perforated and extended beyond the outer wall to provide an externally threaded neck, and a coupling provided with an internally 85 threaded pocket, the threaded neck of the inner wall of the body portion fitting into the pocket of said coupler and the coupler forming a closure for the space between the inner and outer walls of the body portion. 90

3. A mouth-piece of the character described comprising a body portion having an outer wall and an inner wall extending beyond the outer wall to provide a neck, and a coupling provided with a pocket, the neck of the inner wall of the body portion fitting into the pocket of the coupler and the coupler forming a closure for the space between the inner and outer walls of the body portion. 100

In testimony whereof I affix my signature in presence of two witnesses.

SETH M. HINO.
